HEIGHT MEASURING SCALE

Merwin Guy Hall, Rte. 1, Box 268,
Covington, La. 70433

Filed Oct. 12, 1972, Ser. No. 296,966

Term of patent 14 years

Int. Cl. D10—04

U.S. Cl. D52—6 A

FIG. 1 is a front elevational view of a height measuring scale, showing my new design;

FIG. 2 is a side elevational view thereof;

FIG. 3 is a top plan view thereof;

FIG. 4 is a front perspective view thereof with the blade in a folded position.

I claim:

The ornamental design for a height measuring scale, as shown and described.
